EDWARD C. SCHINKE, OF WEBSTER GROVES, MISSOURI. ASSIGNOR TO THE ACCOUNTOGRAPH COMPANY, OF ST. LOUIS, MISSOURI, A CORPORATION OF MISSOURI.

CALCULATING MACHINE.

Application filed March 31, 1923. Serial No. 629,214.

This invention relates to improvements in calculating machines, and to illustrate certain features of the invention I have shown calculating mechanism adapted to be actuated by the numeral keys and platen carriage of an ordinary typewriter. One of the objects of the invention is to provide an improved means for actuating and controlling a plurality of accumulators, or totalizers. 5 The machine herein shown and described is provided with a plurality of accumulators and each accumulator can be selected and operated by itself, or two or more accumulators can be selected and operated at the same time. The selection of the accumulators is preferably under the control of individual selectors that can be readily positioned for the most desirable selection of the accumulators, and the selection will depend 10 upon the particular kind of work to be performed by the machine. After being properly positioned, the selectors automatically select the accumulators at the times they are to be operated, and the machine preferably 15 includes manually operated keys whereby any one or all of the selectors may be rendered ineffective.

The machine about to be described also includes key-controlled devices through 20 which motion is transmitted for addition and subtraction, and automatic means determining whether the operation is to be addition or subtraction. This automatic means is preferably associated with the selectors 25 for the accumulators, so as to predetermine whether addition or subtraction is to be performed in the selected accumulator.

Each accumulator is provided with an actuator and a traveling denominational carriage, movable step by step to change the denominational relation of the actuator to the accumulator, thereby providing for the transmission of movement to a series of total wheels of different orders. The actuator just referred to may be a rotary master wheel, and it may be carried by the denominational carriage so as to advance one step in response to each operation of the numeral keys. In the structure I have shown, the 45 denominational carriage is driven by the traveling platen carriage of an ordinary typewriter.

Briefly stated, the preferred form of the invention comprises a plurality of accumulators each provided with an actuator in the 55 form of a master wheel, and a denominational carriage movable step by step to simultaneously change the denominational relation of the master wheels to the respective accumulators. When all of the accumulators are to be actuated, the denominational carriage locates the master wheels in their operative positions relative to the accumulators, and when only one accumulator is to be actuated, the denominational carriage is 60 shifted to locate one of the master wheels in successive operative positions relative to its accumulator, while the other master wheels are located in successive idle positions relative to their accumulators. In either case 65 the denominational carriage simultaneously locates all of the master wheels in different positions relative to the accumulators, so it is not necessary to employ more than one denominational carriage and it is not necessary to provide mechanism for causing one 70 denominational carriage to travel independently of another.

This may be accomplished by causing one of the master wheels to occupy idle positions between denominational wheels of its accumulator, while another master wheel occupies active positions in mesh with the wheels of its accumulator. By means of an extremely simple selecting device, all of the 80 master wheels can be located in their operative positions to simultaneously actuate the accumulators. As an illustration of this 85 feature of the invention, I have shown thin master wheels adapted to idly rotate between adjacent denominational wheels of the accumulators, and also adapted to mesh with the denominational wheels of the accumulators. The means for actuating the traveling denominational carriage is provided 90 with traveling selectors whereby each accumulator can be selected and shifted from an idle position to an active position wherein its denominational wheels are adapted to mesh with one of the master wheels.

With the foregoing and other objects in view, the invention comprises the novel construction, combination and arrangement of parts hereinafter more specifically de-

scribed and illustrated in the accompanying drawings wherein is shown the preferred embodiment of the invention. However, it is to be understood that the invention comprehends changes, variations and modifications which come within the scope of the claims hereunto appended.

Fig. I is a side elevation, partly in section, showing a typewriting machine provided with calculating mechanism embodying the features of this invention.

Fig. II is a detail view of parts of the means for shifting a reversing gear.

Fig. III is a view similar to Fig. II showing the parts in different positions.

Fig. IV is a top view, partly in section, of the calculating mechanism below the typewriter.

Fig. V is a side elevation of certain selectors and other elements at the rear upper portion of the machine.

Fig. VI is a rear view of the mechanism shown by Fig. V.

Fig. VII is a front view, partly in section, showing the elements at the rear of the machine.

Fig. VIII is a detail view of some of the elements at the upper portion of Fig. VII, showing some of the parts in different positions.

Fig. IX is a bottom view of parts at the front of the machine, showing some of the elements of the accumulator selecting means.

Fig. X is an enlarged side elevation, partly in section, showing means through which motion is transmitted from numeral keys to the master wheel shaft.

Fig. XI is a perspective view showing the housing of one of the accumulators and the shifter for moving the accumulator from an idle position to an active position.

Fig. XII is a detail view of the shifter for the reversing gear on the master wheel shaft.

Fig. XIII is a transverse section looking toward the front of the machine, and showing the master wheel carriage whereby the master wheels are shifted on their shaft.

Fig. XIV is a diagrammatical view of the tripable devices whereby the platen carriage is connected to the means for driving the master wheel carriage.

Fig. XV is a fragmentary view of a part of the means for disconnecting the calculating mechanism from the typewriter keys.

Fig. XVI is a diagrammatical view of the traveling selectors and the shifters actuated thereby.

Briefly stated, the machine about to be described is a calculating attachment for typewriters, and it is adapted for use with ordinary typewriting machines now on the market. The numbers to be added are written by the typewriter and the total is in-

dicated by an accumulator, or by a plurality of accumulators. Each of the accumulators herein shown comprises a series of denominational wheels, or total wheels of different order, and motion is transmitted from a master wheel to the total wheels. Either the master wheel or the accumulator must travel step by step in response to the key operations, so as to change the denominational relation of the master wheel to the accumulator. The master wheel is therefore splined to a rotary shaft and carried by a master wheel carriage, or denominational carriage, adapted to travel in unison with the platen carriage of the typewriter. The master wheel is rotated through the medium of the numeral keys of the typewriter.

The accumulators.

I do not deem it necessary to point out all of the details of construction of an accumulator, such devices being old and well known in the art, and no claim is herein made for an accumulator per se. To illustrate certain features of the invention, I have shown in a more or less conventional manner three accumulators designated A, B and C wherein items are added and subtracted. As will be hereinafter described, these accumulators may be actuated simultaneously, and they may be actuated independently of each other for either addition or subtraction.

Each accumulator herein shown comprises a housing 1 slidably mounted on horizontal rods 2 at the front of the machine. Each housing is provided with total indicating wheels 3, (Figs. I, IV and X) which may be viewed through a sight opening in the top of the housing, and transmission wheels 4 meshing with the total wheels 3 and adapted to be driven by a master wheel. The wheels 4 may be termed denominational wheels for they actuate the total wheels 3 of different denominations. A' designates the master wheel associated with the accumulator A, and B' designates the master wheel for accumulator B. C' is the master wheel of accumulator C. All of the master wheels are splined to a rotary shaft 5, and when in service they travel step by step, longitudinally of the shaft 5, so as to successively mesh with the denominational wheels 4 in the accumulators. The master wheel shaft 5 is rotated through the medium of the numeral keys, as will be hereinafter described.

The master wheel carriage, or denominational carriage, comprises a frame 6 provided with fingers 7, each of said fingers extending into an annular groove in the hub of a master wheel. The frame 6 is provided with rollers 8 engaging stationary horizontal tracks 9 parallel with the master wheel shaft 130

5. It is to be understood that the master wheel carriage including frame 6 and fingers 7 can be shifted along the stationary tracks 9 to locate the master wheels in different positions relative to their accumulators.

Feeding the master wheels.

To change the denominational relation of the master wheels to the accumulators, each of the master wheels is movable step by step along the master wheel shaft 5, and these movements are obtained by transmitting power from the platen carriage of the typewriter to the master wheel carriage. The master wheel carriage is provided at its lower edge with a toothed rack 10 (Fig. I and XII) meshing with a sector 11 fixed to a long oscillatory shaft 20, which extends approximately from the front to the rear of the machine. A sector 21 (Figs. I and VII) is rigidly secured to the rear end of the long shaft 20, and this sector 21 meshes with teeth at the lower edge of the long feeding lever 22, said lever being detachably secured to the typewriter by means of a pivot screw 23.

E designates the platen carriage of the typewriter (Fig. I), said carriage being adapted to travel back and forth in a straight horizontal line, and it may be actuated in response to the key operations, as is well understood in this art, the carriage moving one step in response to each key operation. The rear portion of the platen carriage is provided with a long toothed horizontal bar 24 (Figs. I, V and VI), a bar of this kind being present in the carriages of several well known typewriters now on the market. K, K' and K² designate pin-carrying clips straddling the toothed bar 24 and adjustably mounted thereon. Each of these clips is provided with a power transmission pin 25 adapted to cooperate with certain elements at the upper end of the long lever 22, for the purpose of transmitting movement from the platen carriage to said long lever 22. The fingers at the upper end of the lever 22 cooperate in a peculiar manner with the pins 25 as will be hereinafter described, but it should now be understood that the long lever 22 oscillates in response to movements of the platen carriage, and that motion is thus transmitted from the long lever 22 to the sector 21 at the rear of the machine, and thence through the long driving shaft 20 (Figs. I and V) to the sector 11 which meshes with the rack 10 on the master wheel carriage. Motion is thus transmitted from the traveling platen carriage to the master wheel carriage.

Transmitting movement from key levers to the rotary master wheel shaft.

The key lever 42 (Fig. I) forms part of the typewriting machine, and may be con-

sidered as one of the numeral key levers with which typewriting machines are ordinarily equipped, it being unnecessary to change the keyboard of the typewriting machine used with the calculating attachment. 70 43 designates a key lever extension (Fig. I) secured to the numeral key lever 42 and provided with a pin 44 through which motion is transmitted to the calculating machine. Each numeral key lever is provided with an 75 extension 43. Vertically guided slide bars 45 (Figs. I and IV) are connected by means of levers 46 to the key extensions 43, each of said levers 46 (Fig. I) being pivoted to the upper end of one of the vertical slide 80 bars 45 and provided at its upper end with a hook adapted to receive the pin 44 on one of the key extensions 43. These connecting levers 46 are used to transmit power from the numeral keys to the slide bars 45, and 85 each of said levers 46 can occupy the operative position shown by Fig. I, wherein the hook at the upper end of the lever is engaged with pin 44 on a key extension, or 90 said levers 46 can be shifted to idle positions 95 wherein their hooks are disengaged from pins 44, so as to allow the numeral keys to be operated without transmitting movement to the calculating mechanism. The means for shifting the levers 46 will be hereinafter described.

There are ten of the vertical slide bars 45 (Fig. IV) representing the digits 0 to 9, inclusive, and each of these slide bars, excepting the bar associated with the 0 key, is 100 provided with means for transmitting movement to an oscillatory digit wheel shaft 47. 47 designates restoring springs (Figs. I and X) tending to retain the slide bars 45 in 105 their elevated positions. The slide bar 45 associated directly with the 1 key will drive the digit wheel shaft 47 a distance corresponding to one step of the calculating operation, the slide bar 45 representing the digit 2 being adapted to drive said shaft 47 110 a distance of two steps, etc., the 9 key being adapted to drive said shaft nine steps, all of which is well understood in this art.

To accomplish this, each of the slide bars 45 representing the digits 1 to 9, inclusive, 115 may be provided with a predetermined number of rack teeth 45' adapted to mesh with a toothed digit wheel 48 (Figs. I, IV and X), the digit wheels being rigidly secured to the digit wheel shaft 47 and the racks 120 being formed on the respective slide bars. It will now be understood that the numeral keys representing digits 1 to 9, inclusive, are used to actuate slide bars 45 whereby the digit wheel shaft 47 is actuated, and the 125 degree of movement imparted to the digit wheel shaft will depend upon the value of the key from which motion is transmitted. In Fig. I a screw 27 is located beneath a slide bar 45 to limit its downward motion, 130

and each slide bar may be provided with an adjustable stop of this kind.

The means for transmitting movement from the digit wheel shaft 47 to the master wheel shaft 5 is shown most clearly in Figs. I, IV and X. The digit wheel shaft 47 oscillates in response to the movements of the vertical slide bars 45, but the master wheel shaft 5 is driven continually in only one direction during the adding operations. 49 designates a ratchet wheel fixed to the digit wheel shaft 47, and 50 designates a gear wheel loosely mounted on said shaft. A pawl 51, (Fig. X) engaging the ratchet wheel 49, is pivotally secured to the gear wheel 50. The train of gearing through which motion is transmitted comprises a large gear 52 (Figs. I, IV and X) meshing with the gear wheel 50, a pinion 53 meshing 20 with the large gear 52, and a shiftable gear 55 adapted to mesh with the pinion 53 for subtraction, and also adapted to mesh with the gear 52 for addition. This shiftable gear 55 is splined to the master wheel shaft 5. A pawl 56 (Fig. X) cooperates with the large gear 52 to prevent retrograde movement of the train of gearing. This train of gearing, including the ratchet and pawl 49, 51, transmits rotary movement to the master 25 wheel shaft 5 in response to the oscillatory movements of the digit wheel shaft 47, and when the machine is in service, the master wheels travel along the shaft 5, advancing step by step from one accumulator wheel to another, so as to successively actuate the different total wheels. For example, to introduce the numeral 29 into an accumulator, the 2-key is depressed while the master wheel registers with an accumulator wheel 4 in 30 the tens order. The total wheel in the tens order is thus turned 2 steps, and the master wheel is then driven by the platen carriage so as to pass to the units order. Thereupon, the 9-key is depressed, with the result of 35 actuating the total wheel in the units order, driving it nine steps.

Subtraction.

In subtracting one number from another, 59 the master wheel shaft must be rotated reversely to the direction in which it is driven for addition. The relatively wide or thick reversing pinion 53 (Figs. IV and X) is therefore permanently in mesh with the gear wheel 52 through which motion is transmitted from the digit wheel shaft to the master wheel shaft, and the shiftable gear wheel 55 on the master wheel shaft can mesh directly with the pinion 53 to subtract numerals from the accumulator, and said gear wheel 55 can be located in the position shown in Fig. IV so as to mesh with the wheel 52.

The means for shifting the gear wheel 55 (Figs. X, XII and XIII) comprises a lever

58 pivotally supported at 59 and extending into an annular groove in the hub of said wheel 55. By operating the lever 58, the gear 55 can be placed in mesh with either the gear wheel 52 for addition or the reversing pinion 53 for subtraction. This lever 70 can be manually operated, and it is operated automatically as will be hereafter described.

Disconnecting the numeral keys from the calculating mechanism.

I have previously referred to connecting levers 46 (Fig. I) having hooks whereby the numeral keys are detachably connected to the calculating mechanism. Each lever 46 has a depending leg 46' which extends between a pair of long horizontal rods 64 (Figs. I and IV) secured to oscillatory arms 65. These arms 65 are actuated to move the levers 46 to connect the calculating mechanism to the typewriter, and also to disconnect the calculating mechanism when the numeral keys are to be operated independently of the calculating mechanism. The arms 65 are fixed to an oscillatory shaft 66 (Figs. I and XV) provided with an operating arm 67. A spring 68 (Fig. I) tends to move the arms 65 toward the front of the machine, thereby tending to connect the upper ends of levers 46 to the numeral key levers. Note that a roll on the operating arm 67 (Figs. I and XV) is adapted to be engaged by the top face of an arm 69 on the long shaft 20. If the shaft 20 is turned in one direction, the arm 69 will move upwardly to impart a forward movement to the lower end of arm 67, thereby actuating the arms 65 and rods 64 to disconnect the calculating mechanism from the numeral keys. If the shaft 20 is then turned in the opposite direction, it will lower the arm 69, and thereby permit the spring 68 (Fig. I) to connect the calculating mechanism to the key levers as shown in the drawings. It will therefore be understood that the oscillatory shaft 20, which transmits movement from the platen carriage to the master wheel carriage, also serves as means for connecting and disconnecting the key levers. When the platen carriage of the typewriter reaches a predetermined field, it begins to transmit movement to the long shaft 20 so as to actuate the master wheel carriage, and when the platen carriage passes from said field it releases the shaft 20 and permits the latter to be restored by a spring 70 (Figs. IV and XIII) at the master wheel carriage thereby causing the arm 69 to engage and actuate the operating arm 67 so as to disconnect the calculating mechanism from the key levers. The restoring spring 70 is connected to the master wheel carriage, and said carriage is provided with a rack bar 10 meshing with sector 11 on the shaft 20.

Connecting the platen carriage to the means for feeding the master wheel carriage.

When the platen carriage of the typewriter reaches a predetermined position, it begins to transmit movement to the means for feeding the master wheel carriage, and after the master wheels pass entirely across their accumulators, the feeding means is disengaged from the platen carriage, permitting the latter to continue in motion without advancing the master wheel. I have already briefly described the means for transmitting movement from the traveling platen carriage to the traveling master wheel carriage, and attention is now directed to the means whereby the platen carriage is connected to and disconnected from the long feeding lever 22 at the rear of the type-writing machine.

This feeding lever (Figs. I and V) is in the form of a sector meshing with the sector 21 at the rear of the long shaft 20 through which movement is transmitted to the master wheel carriage at the front of the machine. The power transmission pins 25 secured to the adjustable clips at the rear portion of the platen carriage, form parts of the means for connecting said platen carriage to the feeding lever 22. 83 designates a restoring spring tending to retain the lever 22 in the position shown by Fig. VI, where it engages a stationary stop pin 83'. An elongated tripable abutment finger 84 is pivotally mounted on a pin 85 (Figs. V, VI, VII and XIV) carried by the long lever 22, the axis of the pivot being approximately parallel with the horizontal path of the platen carriage. This tripable finger 84 extends into the path of the pins 25, so as to transmit movement from said pins to the lever 22. As shown most clearly in Figs. V and VI, 86 designates a spring tending to retain the finger 84 in the path of the traveling pins 25. 84' designates a retaining finger parallel with the finger 84 and movable into the path of the traveling pins 25 so as to cooperate with the finger 84 in connecting the platen carriage to the long lever 22. The finger 84' is supported on the pivot 85, and a spring 86' (Fig. VI) tends to retain the upper end of this finger 84' in the path of the traveling pins 25. The fingers 84 and 84' move with the long lever 22 and they lie between stationary cams 87 and 87'. (Figs. VI and XIV) each finger having an inclined edge adapted to engage a correspondingly inclined face on one of the cams. Through the medium of these cams, the pivoted fingers 84 and 84' are shifted laterally to positions beyond the path of the pins 25.

When the long lever 22 occupies its starting position, the fingers 84 and 84' lie in the positions shown by full lines in Figs. VI and

XIV and by dotted lines at the left side of Fig. XIV. A traveling pin 25 can then pass the finger 84' and engage the finger 84 to transmit motion to the lever 22. At the beginning of this motion, the finger 84' passes from cam 87' and its spring 86' then shifts the finger 84' to a position in alinement with the finger 84. The pin 25 then lies between the fingers 84 and 84' and movement can be transmitted in either direction from the platen carriage to the long lever 22 whereby the master wheel carriage is operated.

When the master wheels travel entirely across their accumulators, the finger 84 is tripped by the cam 87, as shown by dotted lines at the left side of Fig. XIV, thereby permitting the spring 86 to quickly restore the lever 22. The pin 25 can then continue in motion with the platen carriage, without driving the lever 22. Thereafter, the other traveling pins 25 will cooperate with the fingers 84 and 84' in the same manner to actuate and then release the long lever 22 and the master wheel carriage driven thereby.

When the platen carriage is eventually restored, the spring pressed fingers 84 and 84' will occupy the positions shown by full lines at the right side of Fig. XIV, and the traveling pins 25 will engage the inclined face of finger 84, so as to shift said finger out of the path of the pins.

Automatically selecting the accumulators.

When one of the traveling pins 25 transmits motion from the platen carriage to the long lever 22, the master wheel carriage is actuated to simultaneously shift all of the master wheels A', B' and C' along the rotary shaft 5 to which said wheels are splined. One master wheel cannot be shifted independently of the others, and all of the master wheels are rotated at the same time through the medium of shaft 5 which is driven by the numeral keys. However, any one of the accumulators can be actuated independently of the others, and any two or all three of the accumulators can be actuated at the same time.

Although the three master wheels A', B' and C' travel step by step at the same time to mesh with their successive denominational wheels 4, it will be observed that the space between any two adjacent wheels 4 (Fig. IV) is greater than the thickness of a master wheel, and it is possible for a master wheel to idly rotate in the successive spaces between its denominational wheels 4. Therefore, the accumulators are slidably mounted on horizontal rods 2 parallel with the master wheel shaft 5, and each accumulator can be shifted a slight distance to the left for the purpose of locating its denominational wheels 4 in active positions where they will be actuated by their master wheel. If an ac-

cumulator is permitted to remain in its idle position, shown by Fig. IV, its master wheel will travel step by step with the other master wheels, but the master wheel associated with the idle accumulator will rotate idly in the spaces between its denominational wheels 4. The means for selecting the accumulators comprises automatic devices whereby the accumulators to be operated are shifted to the left from the positions shown in Fig. IV, and the selected accumulators are thus positioned for actuation by their master wheels.

When an accumulator occupies its idle position, its housing engages a stop-collar 90 on one of the rods 2 and it is held there by means of a restoring spring 91 (Figs. I, IV and XI). Each accumulator is also provided with a shifter comprising a lever 92 pivoted at 93 and adapted to engage an abutment lever 94 (Figs. I, IV and XI) pivoted to one side of the accumulator housing. When the abutment lever 94 occupies the position shown in Figs. I and XI, it is held in engagement with a stop pin 95 by means of a spring 96, and if the shifting lever 92 is then operated, it will engage the abutment lever 94 to shift the accumulator. However, each abutment lever has an extended handle which may be depressed by the operator to locate said lever below the path of the upper end of the adjacent shifting lever 92, and in this event the shifting lever cannot displace the accumulator from its idle position. Consequently, each abutment lever 94 serves as a manually operable key adapted to prevent the selection of its accumulator.

After an abutment lever 94 has been depressed, it is held by the operator until the adjacent shifting lever 92 has been moved toward the accumulator, and it can then be released and permitted to engage the lower edge of the extended upper end of shifting lever 92. When the shifting lever is eventually restored, it will release the depressed abutment lever 94, and the latter will be restored by its spring 96.

The automatic means for shifting the levers 92 to select the accumulators comprises arms 97 pivoted at 98 and adapted to engage rolls on the lower ends of the respective shifting levers 92. The means for actuating these arms 97 is shown most clearly by Fig. XVI. Bell crank levers 99, at the rear lower portion of the machine, are connected by means of rods 100 to the respective arms 97, and to each bell crank 99 is connected a rod 101 extending upwardly therefrom and having its upper end connected to a bell crank lever 102. There are three of the levers 102, one for each accumulator, and each of these levers 102 can be operated to transmit the shifting movement whereby its accumulator is shifted and thus selected for operation by its master wheel. The three levers 102 are all pivotally supported on a

pin 103 and provided with operating extensions *a*, *b* and *c* which lie in different planes below the toothed bar 24 on the traveling platen carriage.

Each of the adjustable clips K, K' and K², traveling with the bar 24, is provided with one or more depending selectors designated by A², B² and C², and shown most clearly in Fig. XVI. Each of these traveling selectors is pivoted to one of the clips (Fig. VI) and provided with an upward extension 104 adapted to engage the clip to limit the pivotal motion in one direction. The traveling selector A² is adapted to engage and actuate the operating extension *a* of the bell crank lever 102 associated with accumulator A, so as to shift said accumulator from its idle position to its active position. The selector B² is adapted to likewise engage and actuate the operating extension *b* associated with accumulator B, and the selector C² is adapted to engage and actuate the extension *c* to shift the accumulator C. This is suggested by Fig. XVI, wherein the traveling selectors moving to the left are arranged to first select the accumulator A which is operated independently of the other accumulators, this selection being accomplished through the medium of selector A² engaging operating extension *a* to transmit the shifting motion to accumulator A which lies at the left side of the machine. Thereafter, the selectors B² and C² carried by clip K', engage and actuate the operating extension *b* and *c* to shift the middle accumulator B and the right hand accumulator C, both of which are then operated independently of accumulator A, and after the operations in these two accumulators have been completed, the selector C² engages operating extension *c* to provide for independent operation of accumulator C. It will be apparent that the selectors can be readily rearranged or modified to provide for any desired selection of the accumulators.

In moving to the left (Figs. VII, VIII and XVI) the selectors actuate the operating extensions while the members 104 are engaged with the traveling clip to limit the pivotal motion of the selectors, but when the traveling platen carriage is restored by a movement in the opposite direction, the selectors idly ride over the operating extensions *a*, *b* and *c*, while the extensions 104 move away from the clips.

After an accumulator has been selected and shifted, it is locked in its operative position through the medium of a latch member 105 (Fig. VIII and XVI). There are three latch members 105, one for each accumulator, and each latch member is pivoted to one of the bell crank levers 102 and provided with a shoulder 106 adapted to engage a stationary bar 107 to retain the selected accumulator in its operative position. After the

operation in the selected accumulator has been completed, the latch member is released, as will be presently described, and the accumulator is then shifted to its idle position by means of its restoring spring 91.

The means for unlocking the latch bars 105 (Figs. VI, VII and VIII) comprises a pin 108 carried by the large oscillatory lever 22 through which motion is transmitted from 10 the platen carriage to the master wheel carriage. Upon the completion of a calculating operation, the pin 108 engages a cam face 109 on the bottom of the selected latch member 105, so as to lift said latch member and 15 release its shoulder 106 from the stationary bar 107, thereby releasing the selected accumulator and permitting it to return to its idle position. Immediately thereafter, the large lever 22 is released from its traveling 20 operating pin 25 and restored to the position shown by Figs. VI and VII.

Under some conditions the pin 108 may fail to release the latch member, or members 105. For example, the calculating operation 25 may be completed and the operator may restore the platen carriage before the pin 108 strikes the cam faces on the latch member. Or, if the carriage operation is very rapid, the latch member may fall back to its locking 30 position after being released by the pin 108. Therefore, the unlocking means for the latch members preferably includes an additional 35 unlocking device which becomes effective when the long lever 22 is restored to the position shown by Figs. VI and VII. This additional device is an arm 110 pivoted at 111 and having an extension 112 at its free end arranged to lie under the ends of the latch members 105 when the latter occupy their 40 locking positions. This arm 110 is provided with an operating finger 113 adapted to be engaged by pin 108 when long lever 22 occupies the starting position shown by Figs. VI and VII. Consequently, when lever 22 45 is restored, the pin 108 engages finger 113 to elevate the free end of any latch member 105 that occupies its locking position. The latch members can thus be released from the stationary bar 107.

50 *Automatic control of addition and subtraction.*

I have previously referred to the gear 55 splined to the reversible master wheel shaft 53 and adapted to mesh with gear wheel 52 for addition, or reversing pinion 53 for subtraction. The shiftable gear 55 is shifted by means of lever 58 having a pin 58' extending into an annular groove in the hub of said gear. This lever 58 can be operated by hand, and it is also operated automatically to provide for the selection of either addition or subtraction. After being shifted, the lever 58 is yieldingly held by means of a 60 spring actuated detent arm 114 (Figs. IX 65

and XII) having two notches adapted to receive the lower end of said lever.

The automatic means for shifting the lever 58 comprises a bell crank lever 115 (Figs. IX and XVI) slotted to receive the lower 70 end of lever 58 and connected by means of a rod 116 to a bell crank lever 117 at the rear of the machine. 118 designates a rod connecting the bell crank lever 117 to an arm 119, the latter being pivoted at 120 and 75 provided at its free end with a roll 121 adapted to be engaged by pins 122 and 123 extending rearwardly from the traveling clips K, K' and K².

The traveling pins 122 are positioned to 80 ride over the roll 121 so as to depress the arm 119 (Fig. II) and the pins 123 are positioned to travel under and thereby elevate the arm 119 (Fig. III). When said arm is moved upwardly, it actuates the shifter lever 85 92 to provide for addition, and when said arm 119 is depressed it moves the shifter lever to the subtracting position. Each of the traveling clips K, K' and K² carries one 90 of the pins 122 or 123, and each of these pins 95 may be termed "a selector" for the reason that it automatically selects either addition or subtraction. This selection is made at about the time the master wheel carriage begins its step by step motion, and at this time 95 the accumulator, or accumulators, are also selected.

It will be understood that the automatic selection of the accumulators, as well as the automatic selection for addition and subtraction can be modified to obtain the most desirable results for different kinds of work, the traveling clips being adjustable and removable, so that they can be readily removed and rearranged or replaced by clips having 100 the desired selectors thereon. Any desired number of accumulators may be used, and any of the accumulators herein shown can be eliminated from the calculating operations by removing the clip with the selector for 105 that accumulator.

I claim:

1. In a calculating machine, a plurality of accumulators each provided with a series of toothed denominational wheels and a toothed rotary actuator adapted to mesh with said wheels and also adapted to occupy idle 115 positions between adjacent denominational wheels, each of the rotary actuators being movable step by step to mesh with its different denominational wheels and also from one of said idle positions to another, certain of the teeth of said actuators passing through the spaces between teeth of said denominational wheels when said actuators pass from one idle position to another, and selectors 120 adapted to establish an operative relationship between said actuators and their denominational wheels, each of said selectors being 125 associated with one of said accumulators to 130

control the transmission of movement thereto.

2. In a calculating machine, a plurality of accumulators each provided with a series of toothed denominational wheels and a toothed rotary actuator adapted to mesh with said wheels and also adapted to occupy idle positions between adjacent denominational wheels, each of the rotary actuators being movable step by step to mesh with its different denominational wheels and also from one of said idle positions to another, certain of the teeth of said actuators passing through the spaces between teeth of said denominational wheels when said actuators pass from one idle position to another, a traveling denominational carriage whereby the step by step movement is simultaneously imparted to all of said actuators, key-controlled means whereby all of said actuators are simultaneously rotated to actuate the denominational wheels in mesh with an actuator while the actuator between adjacent denominational wheels is idly rotated, and selectors adapted to establish an operative relationship between said actuators and their denominational wheels, each of said selectors being associated with one of said accumulators to provide for independent operation of the selected accumulator while the actuator of the other accumulator is idly rotated between denominational wheels.

3. In a calculating machine, an accumulator provided with a series of toothed denominational wheels and a toothed rotary actuator movable step by step to mesh with the successive denominational wheels, said actuator being also adapted to occupy successive idle positions between and not in mesh with adjacent denominational wheels, certain of the teeth of said actuator passing through the spaces between teeth of said denominational wheels when said actuator passes from one idle position to another, key-controlled means whereby said actuator is rotated to drive the accumulator while in mesh with said wheels and to rotate independently of the accumulator while in said idle positions, and means whereby said accumulator is shifted from an active position wherein said actuator meshes with the denominational wheels to an idle position permitting independent operation of the actuator between said wheels.

4. In a calculating machine, an accumulator provided with a series of toothed denominational wheels and a toothed rotary actuator movable step by step to mesh with the successive denominational wheels, said actuator being also adapted to occupy successive idle positions between and not in mesh with adjacent denominational wheels, certain of the teeth of said actuator passing through the spaces between teeth of said denominational wheels when said actuator is

moved from one idle position to another, key-controlled means whereby said actuator is rotated to drive the accumulator while in mesh with said wheels and to rotate independently of the accumulator while in said idle positions, and means whereby said accumulator is shifted from an active position wherein said actuator meshes with the denominational wheels to an idle position permitting independent operation of the actuator between said wheels, the last mentioned means including a traveling selector and a shifter actuated thereby to shift the accumulator from one of said positions to another.

5. In a calculating machine, a plurality of accumulators each having wheels and provided with an actuator, a traveling denominational carriage movable step by step to simultaneously change the denominational relation of the actuators to their respective accumulators, each of said accumulators being shiftable in a straight line from an idle position where all of its wheels are offset from its actuator to an active position wherein one of its wheels is in alinement with said actuator and may be driven thereby, and traveling selectors whereby said accumulators are shifted, each of said selectors being associated with one of said accumulators to provide for the shifting and independent operation of the selected accumulator.

6. In a calculating machine, a plurality of accumulators each provided with a series of denominational wheels and a rotary actuator adapted to mesh with said wheels, a traveling denominational carriage movable step by step to simultaneously change the denominational relation of the actuators to their respective accumulators, key-controlled means whereby said actuators are rotated at the same time to simultaneously actuate the accumulators, each of said accumulators being shiftable in a straight line from an active position wherein one of its denominational wheels is in alinement with its actuator and may be driven thereby to an idle position wherein said actuator is offset from said denominational wheels thus permitting independent operation of the actuator, and traveling selectors whereby each accumulator is selected and shifted from one of said positions to the other.

7. In a calculating machine, a plurality of accumulators each provided with a series of denominational wheels and a rotary actuator adapted to mesh with said wheels, a traveling denominational carriage movable step by step to simultaneously change the denominational relation of the actuators to their respective accumulators, key-controlled means whereby said actuators are rotated at the same time to simultaneously actuate the accumulators, each of said accumulators being shiftable in a straight line from an active position wherein one of its denominational

wheels is in alinement with its actuator and may be driven thereby to an idle position wherein said actuator is offset from said denominational wheels thus permitting independent operation of the actuator, and traveling selectors whereby each accumulator is selected and shifted from one of said positions to the other, each of said traveling selectors being associated with one of said accumulators to provide for independent operation of the selected accumulator while all of said actuators are rotated by said key controlled means.

8. In a calculating machine a plurality of accumulators each provided with a series of denominational wheels, a rotary actuator adapted to mesh with said denominational wheels and also adapted to rotate between adjacent denominational wheels, a traveling denominational carriage movable step by step to simultaneously change the denominational relation of the actuators to their respective accumulators, key-controlled means whereby said actuators are rotated at the same time to simultaneously actuate the accumulators, each of said accumulators being shiftable in a straight line from an active position wherein one of its denominational wheels is in alinement with its actuator and may be driven thereby to an idle position wherein the actuator is offset from all of said denominational wheels whereby said actuator may be idly rotated between its denominational wheels, and selectors whereby each accumulator is selected and shifted from one of said positions to the other.

9. In a calculating machine a plurality of accumulators each provided with a series of denominational wheels, a rotary actuator adapted to mesh with said denominational wheels and also adapted to rotate between adjacent denominational wheels, a traveling denominational carriage movable step by step to simultaneously change the denominational relation of the actuators to their respective accumulators, key-controlled means whereby said actuators are rotated at the same time to simultaneously actuate the accumulators, each of said accumulators being shiftable in a straight line from an active position wherein one of its denominational wheels is in alinement with its actuator and may be driven thereby to an idle position wherein the actuator is offset from all of said denominational wheels and may thus be idly rotated between said denominational wheels, and selectors whereby each accumulator is selected and shifted from one of said positions to the other, each of said selectors being movable step by step in synchronism with said denominational carriage and provided with a shifter whereby motion is transmitted to the selected accumulator.

10. The combination of a typewriter having a platen carriage, and calculating mecha-

nism comprising two accumulators each provided with an actuator, a traveling denominational carriage movable step by step to simultaneously change the denominational relation of both actuators to their accumulators, operating means whereby the step by step motion is transmitted from said platen carriage to said denominational carriage, one of said accumulators being shiftable in a straight line from an active position wherein one of its denominational wheels is in alinement with its actuator to an idle position wherein all of its wheels are offset from its actuator and may not be driven thereby, and a traveling selector whereby the last mentioned accumulator is shifted from one of said positions to the other.

11. The combination of a typewriter having a platen carriage, and calculating mechanism comprising two accumulators each provided with an actuator, a traveling denominational carriage movable step by step to simultaneously change the denominational relation of both actuators to their accumulators, operating means whereby the step by step motion is transmitted from said platen carriage to said denominational carriage, one of said accumulators being shiftable in a straight line from an active position wherein one of its denominational wheels is in alinement with its actuator to an idle position wherein all of its wheels are offset from said actuator and may not be driven thereby, and a traveling selector whereby the last mentioned accumulator is shifted from one of said positions to the other, said traveling selector being carried by said platen carriage and provided with a shifter through which motion is transmitted from the platen carriage to the selected accumulator.

12. The combination of a typewriter having a platen carriage and calculating mechanism comprising two accumulators each provided with an actuator, a traveling denominational carriage driven by said platen carriage and movable step by step to simultaneously change the denominational relation of both actuators to their accumulators, each of said accumulators being shiftable in a straight line from an active position wherein one of its denominational wheels is in alinement with its actuator to an idle position wherein all of its denominational wheels are offset from said actuator and may not be operated thereby, selectors carried by said platen carriage, independently movable shifters adapted to shift the respective accumulators from one of said positions to the other, and means whereby motion is transmitted from said selectors to said shifters, each of said selectors being associated with one of the shifters to provide for automatic selection of the accumulators to be operated.

13. In a calculating machine, an accumu-

- lator provided with a rotary actuator and a denominational carriage movable step by step to change the denominational relation of the actuator to the accumulator, key-controlled means whereby said actuator is rotated to actuate the accumulator, said accumulator being adapted to occupy an idle position wherein its wheels are all offset from its actuator thus permitting operation of said actuator and denominational carriage independently of the accumulator, and said accumulator being shiftable in a straight line laterally of the machine from said idle position to an active position wherein one of its accumulator wheels is in alinement with said actuator and may be driven in response to the movements of said actuator and carriage, a traveling selector whereby said accumulator is automatically shifted from one of said positions to the other, and retaining means cooperating with said selector to retain the accumulator in its active position.
14. In a calculating machine, an accumulator having accumulator wheels and provided with a rotary actuator and a denominational carriage movable step by step to change the denominational relation of the actuator to the accumulator, key-controlled means whereby said actuator is rotated to actuate the accumulator, said accumulator being adapted to occupy an idle position wherein its wheels are offset from its actuator thus permitting operation of said actuator and denominational carriage independently of the accumulator, and said accumulator being shiftable in a straight line from said idle position to an active position wherein one of its wheels is in alinement with its actuator and may be driven in response to the movements of said actuator and carriage, a traveling selector whereby said accumulator is automatically shifted from one of said positions to the other, a spring tending to retain said accumulator in its idle position, a retaining member cooperating with said selector to retain the accumulator in its active position, and automatic means for releasing said retaining member upon the completion of a calculating operation.
15. In a calculating machine, an accumulator having accumulator wheels and provided with a rotary actuator and a denominational carriage movable step by step to change the denominational relation of the actuator to the accumulator, key-controlled means whereby said actuator is rotated to actuate the accumulator, said accumulator being adapted to occupy an idle position wherein all of its wheels are offset from its actuator thus permitting operation of said actuator and denominational carriage independently of the accumulator, and said accumulator being shiftable in a straight line
- from said idle position to an active position wherein one of its wheels is in alinement with its actuator and may be driven in response to the movements of said actuator and carriage, a traveling selector whereby said accumulator is automatically shifted from one of said positions to the other, a spring tending to retain said accumulator in its idle position, a retaining member cooperating with said selector to retain the accumulator in its active position, and automatic means for releasing said retaining member upon the completion of a calculating operation, said accumulator being shiftable in a straight line laterally of the machine from said idle position to an active position wherein one of its wheels is in alinement with its actuator and may be driven in response to the movements of said actuator and carriage, a traveling selector whereby said accumulator is automatically shifted from one of said positions to the other, a spring tending to retain said accumulator in its idle position, a retaining member cooperating with said selector to retain the accumulator in its active position, and automatic means for releasing said retaining member upon the completion of a calculating operation, said automatic means including a releasing member movable in synchronism with said selector and adapted to engage said retaining member.
16. In a calculating machine, a plurality of accumulators each having accumulator wheels and provided with an actuator, a traveling denominational carriage movable step by step to simultaneously change the denominational relation of the actuators to their respective accumulators, each of said accumulators being shiftable in a straight line from an idle position wherein its wheels are offset from its actuator to an active position wherein one of its wheels is in alinement with its actuator and may be driven by said actuator, traveling selectors whereby said accumulators are shifted, each of said selectors being associated with one of said accumulators to provide for the shifting and independent operation of the selected accumulator, and latches cooperating with said selectors to retain the selected accumulator in its active position.
17. In a calculating machine, a plurality of accumulators each having accumulator wheels and provided with an actuator, a traveling denominational carriage movable step by step to simultaneously change the denominational relation of the actuators to their respective accumulators, each of said accumulators being shiftable in a straight line from an idle position wherein all of its wheels are offset from its actuator to an active position wherein one of its wheels is in alinement with its actuator and may be driven by said actuator, traveling selectors whereby said accumulators are shifted, each of said selectors being associated with one of said accumulators to provide for the shifting and independent operation of the selected accumulator, latches cooperating with said selectors to retain the selected accumulators in their active positions, automatic means for releasing said latches upon the completion of each calculating operation, and springs tending to retain the accumulators in their idle positions.

In testimony that I claim the foregoing I hereunto affix my signature.

EDWARD C. SCHINKE.
